UNITED STATES PATENT OFFICE.

JOHN C. McLAUGHLIN, OF JERSEY CITY, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,140,274.

Specification of Letters Patent.

Patented May 18, 1915.

Application filed October 29, 1913. Serial No. 797,963.

To all whom it may concern:

Be it known that I, JOHN C. McLAUGHLIN, a citizen of the United States, residing in Jersey City, in the county of Hudson and 5 State of New Jersey, have invented certain new and useful Improvements in Type-Writing Machines, of which the following is a specification.

My invention relates to ribbon mechanism 10 for typewriting machines, and more particularly to mechanism in which two ribbons, usually of different colors, are adapted to be brought alternately into use, to be vibrated over the printing point when the 15 type-bars are actuated.

The invention provides an improved form 20 of ribbon-vibrating mechanism comprising two ribbon guides movable alternatively to an operative position, and a vibrating lever 25 which is automatically connected with either ribbon guide when the latter is shifted to operative position, and simultaneously disconnected from the other guide as the latter moves to inoperative position. The 30 vibrating lever is mounted to shift up and down with the shift rail on which the platen runs, and carries with it the ribbon guide to which it is connected, so that the active or operative guide maintains the same relation 35 to the platen in both upper and lower case positions. The ribbon guides, which are preferably duplicates and interchangeable, are shiftable alternatively to active position by bell cranks, one arm of each bell crank 40 having a lost motion connection with a ribbon guide, to permit the guide to vibrate over the printing point without moving the bell crank, another arm of each bell crank connected with a shifting bar, the arrangement 45 being such that when the bar is shifted to lift one ribbon guide to active position, the other is simultaneously moved downwardly to inactive position, said shift bar being operatively connected to a key- 50 actuated rock shaft. Said rock shaft also has connection with the vibrator lever for shifting the latter from one guide to the other simultaneously with the shifting of the guides, so that the vibrator is always 55 connected with the active guide and disconnected from the inactive guide.

The vibrator lever may be actuated by a bracket on the universal type-actuated bar of the machine, the bracket having a vertical

slot to receive a pin on the vibrator lever, 55 whereby the amplitude of vibration of the lever is the same for all positions of the latter. The ribbon-shifting mechanism may be locked with both ribbons in an inoperative intermediate position, and the vibrator 60 lever disconnected from both guides.

Other features and advantages will hereinafter appear.

In the accompanying drawings, Figure 1 is a perspective view from the rear showing 65 one form of the invention as applied to an Underwood typewriting machine. Fig. 2 is a fragmentary view illustrating a guide slot in the rear of the type guide and the type-bar segment. Fig. 3 is a perspective view 70 of a ribbon guide. Fig. 4 is a front elevation view showing one of the ribbon guides in operative position and the other silenced. Fig. 5 is a similar view, but with the position of the guides reversed. Fig. 6 is a sec- 75 tional elevation view of the invention, the section being taken from the front to the rear of the machine. Fig. 7 is a similar view showing the position of parts when a type has been moved up to the platen. 80

The platen 1 is carried on a frame 2 mounted on a traveling carriage for movement in letter-feed direction. The platen is shiftable from lower to upper case position by means of a shift rail 3 operable by 85 the usual mechanism (not shown), on which runs a roller 4 on the platen frame. Type-bars 5 are mounted on a pivot rod 6 on a stationary type-bar segment 7, and are actuated by keys 8 pivoted at 9 and connected 90 through bell cranks 10 to the type-bars. The latter carry upper and lower case types 11 and 12, respectively, which, when the keys 8 are depressed, are moved up to the printing point on the front face of the 95 platen, the types as they approach the printing point entering the usual type guide 13, mounted on the segment 7.

Two ribbons 14 and 15 are threaded re- 100 spectively through the front and rear ribbon guides or vibrators 16 and 17. These ribbon guides are preferably identical in construction, therefore interchangeable, and as shown in Fig. 3, each guide comprises eyes 18 through which the ribbon is thread- 105 ed, separated by a space 19 to accommodate the types, and a depending stem 20 pro- vided near its lower end with notches 21

and 22 to accommodate respectively a vibrating lever or actuator and a shifting device for moving the guide into and out of active position.

5 The stem 20 of each ribbon guide is offset laterally with respect to the opening 19, and the guides are in reverse position, that is, the front face of one guide corresponds to the rear face of the other guide, so that 10 the stems 20 are offset on opposite sides of the printing point, thus leaving a space between the said stems. Each of the guides carries a guide pin 23. The pin 23 on the rear guide 17 works in a vertical slot 24 15 formed in a guide bar 25 connected as by screws 26 to the rear face of the type-bar segment, and guides the vibrator 17 in its vertical movement. The pin 23 on the front vibrator enters a vertical slot 27 formed in 20 the type-bar segment and serves to vertically guide the vibrator 16.

The guide bar 25 is offset from the segment 7, as by means of angles 28, to provide a space for the ribbons and guides, and is 25 further provided with a central offset portion 29 to receive and guide the rear vibrator 17. The two ribbon guides or vibrators are selectively movable upwardly into active position by means of shifting devices 30 comprising bell crank levers 30 and 31 co-operating respectively with the front and rear guides 16 and 17. These levers are mounted by means of their pivots 32 on a frame 33 extending parallel with the shift 35 rail 3 and having a rear vertical flange connected as by screws 34 (Fig. 1) to a flattened face of the shift rail, whereby said frame 33 is rigidly connected to the shift rail and moves up and down therewith, the bell 40 crank levers 30 and 31 being pivoted on the vertical front flange of said frame 33. Each of these bell cranks comprises an arm extending laterally toward the ribbon guides, and provided at its inner end with a pin 35, 45 which enters the notch 22 in the adjacent guide. The bell cranks also have upwardly extending arms connected by pivots 36 to a horizontally disposed shift rod or bar 37 connected through a link 38 to a rock arm 39 fixed to a rock shaft 40. A rock bar 41 fixed to the forward end of the rock shaft, carries finger pieces or keys 42 and 43, for rocking said shaft and, through the connections just described, moving the ribbon 50 guides alternatively into active position. When the key 43 is depressed, the shift bar 37 is moved to the right, as shown in Fig. 5, and swings the bell crank 30, so that the pin 35 thereon engages the upper shoulder 55 22^a formed by the notch 22 in the front ribbon guide 16, and shifts said guide to an active position above the type-bar segment. The pin 35 on the bell crank 31 at the same time engages the lower shoulder 22^b of the 60 notch 22 in the ribbon guide 17 and moves 65

the latter to an inactive position below the upper edge of the segment 7, carrying the ribbon 15 with it to inactive position.

The active ribbon is vibrated over the printing point on the platen by means of a 70 universal bar frame 44, operating through an interponent or vibrator lever 45 which forms an actuator for the ribbon vibrators and which may be in the form of a bell crank lever connected by a pivot 46 to the 75 rearwardly extending arm of a bracket 47 fixed as by means of screws 48 to a slide 56 on the rear vertical flange of the frame 33. The universal bar frame 44 is part of a 80 universal bar 49 entering a recess 50 in the segment 7, into the path of shoulders 51 formed on the type-bars 5, so that as each type-bar is moved to printing position, the universal bar is moved rearwardly, and through connections 52, operates the escape- 85 mechanism, not shown.

The vibrator lever 45 comprises an upwardly extending arm carrying a pin 53, which works in a vertical slot 54 in a bracket 55 fixed to the universal bar frame 44, and also comprises a horizontally disposed, forwardly-extending arm, the forward end of which is seated in the notch 21 of the active ribbon guide. When the universal bar is moved rearwardly by the actuation of a 95 type-bar, the lever 45 is moved about its pivot and carries the active ribbon guide upwardly to interpose the ribbon between the type and platen as the type comes up to the printing point. The notch 22 is of such 100 depth as to permit this movement of the ribbon guide without interfering with the shifting lever 30.

The vibrator lever 45 is shiftable laterally into engagement with the active ribbon 105 guide by means of the slide 56 to which it is connected, as already described, said slide 56 being connected through a link 57 to a rock arm 58 fixed to the shaft 40. The slide 56 is supported and guided on the frame 33 110 by means of shouldered screws 59 extending through slots 60 in the slide 56 and threaded into the frame 33.

As shown in Fig. 1, the lever 45 is connected with the forward ribbon guide 16. 115 If the key 42 is depressed to reverse the ribbon guides, the lever 45 through the connections just described, is at the same time shifted to the right (Fig. 1), and thus carried over against the guide 17 as the latter moves upwardly to active position, the arm of the lever 45 being sufficiently resilient to give slightly after it strikes the stem 20 of the guide 17, and slides along the guide until it snaps into position in the notch 21 as the 120 guide completes its movement to active position. If desired, springs 46^a may be mounted on the pivot pin 46 on opposite sides of the lever 45 to permit the lever to yield when brought against the ribbon guides 125 130

during the shifting of the guides and lever. It will thus be seen that the vibrator lever is automatically connected to the active ribbon guide when the latter is moved to active position, and entirely disconnected from the inactive guide, so that only one ribbon is vibrated at any time during the operation of the machine, the inactive guide being positively held in its lowered position by its shifting lever 30 or 31. It will be apparent that when the platen is shifted to upper case position, the lever 45 is moved upwardly bodily and carries the active ribbon upwardly the same distance as the platen is moved. In other words, the relative position of the platen and active ribbon remains unchanged during the platen-shifting movements. The bracket 55 extends upwardly a sufficient distance to maintain an operative connection with the pin 53 when the platen is shifted to upper case position, this connection also effecting the same vibrating movement of the ribbon for any position of the platen. In other words, the amplitude of vibration of the ribbon guide is the same for both upper and lower case positions.

The ribbon guides may be shifted to an intermediate position where they remain below the printing line, permitting the machine to be used for stenciling or other work where it is desired to operate the keys without printing through a ribbon. When in such intermediate position, the actuator 45 is disconnected from both guides so that the latter remain stationary.

The rock shaft 40 carrying the shift keys may be held in either of its operative positions by any suitable means, as for example, 40 that disclosed in the patent to Cook, 926,050, of June 22, 1909. Such means comprises a pin 61 projecting rearwardly from the rock bar 41 into position to coöperate with a spring arm 62 which may be mounted on a bracket 63 on the machine frame, said arm 62 adapted to permit the pin 61 to snap past it as the bar 41 is shifted, thereby holding said bar in either of its shifted positions. To hold said bar in an intermediate position 50 for silencing both ribbons, a lever 64 pivoted at 65 to the bracket 63, is formed with a slot 66 to receive the pin 61 and hold the cross bar 41 in a horizontal position when the lever 64 is moved to the right (Fig. 1) by 55 means of a handle 67. The slot 66 may have its edges beveled to cam the pin 61 either up or down, as the case may require, when the lever is shifted to lock the parts in said intermediate position.

60 Variations may be resorted to within the scope of the invention, and portions of the improvements may be used without others.

Having thus described my invention, I claim:

65 1. In ribbon-vibrating mechanism, the

combination of ribbon guides shiftable alternatively to active position, mechanism to vibrate said guides, and means to automatically disconnect said mechanism from either guide when the latter is moved to inactive position. 70

2. In ribbon-vibrating mechanism, the combination of ribbon guides, a vibrator therefor, means to simultaneously shift the guides to active and inactive positions respectively, and means to simultaneously shift the connections of the vibrator from one to the other of the ribbon guides. 75

3. In ribbon-vibrating mechanism, the combination of a ribbon guide, means to shift said guide into and out of position to be vibrated over the printing point, an actuator to vibrate said guide, and means to automatically connect the actuator and guide when the latter is moved to operative position, and to disconnect the actuator and guide when the latter is moved to inoperative position. 80

4. In ribbon-vibrating mechanism, the combination of ribbon guides vertically shiftable alternatively into and out of active position, and an actuator extending between said guides and laterally shiftable alternatively into and out of operative connection with the guides. 85 90

5. In ribbon mechanism, the combination of ribbon guides having notches therein, means to shift said guides alternatively to active position, and an actuating lever shiftable to alternatively engage said notches and automatically connect the actuating lever to the active guide. 95 100

6. In ribbon mechanism, the combination of ribbon guides, a platen shiftable to upper and lower case positions, a vibrator lever shiftable bodily up and down with the platen, means for vibrating said lever, and means to bodily shift said lever laterally to alternatively engage said ribbon guides. 105

7. In ribbon mechanism, the combination of ribbon guides, a platen shiftable to upper and lower case positions, a vibrator lever shiftable bodily up and down with the platen, means for vibrating said lever, means for selectively shifting the ribbon guides vertically into and out of active positions, and means to simultaneously shift the vibrator lever into operative relation to the guide that is shifted to active position. 110 115

8. In a typewriting machine, the combination of type-bars, a universal bar actuated thereby, ribbon vibrators, an interponent between said universal bar and the vibrators, means to selectively shift the vibrators to active position, and means to simultaneously shift the connections of the interponent from one vibrator to the other. 120

9. The combination of ribbon vibrators, an actuator therefor connected to one vibrator, a manual device for selectively shifting the 130

- vibrators to active position, and means operated by said manual device to shift the connection of said actuator from one vibrator to the other.
- 5 10. The combination of ribbon vibrators selectively movable into and out of active position, a shiftable platen, a vibrator lever bodily shiftable with the platen, and means to shift said lever into engagement with either vibrator.
- 10 11. The combination of ribbon vibrators, shifting devices therefor, means to simultaneously operate said devices to move one vibrator to active position and simultaneously retract the other vibrator to an inactive position, an actuator for the vibrators, and means to connect said actuator with either vibrator.
- 15 12. The combination of ribbon vibrators, shifting devices therefor, means to simultaneously operate said devices to move one vibrator to active position and simultaneously retract the other vibrator to an inactive position, an actuator for the vibrators, and means to maintain said actuator at all times in operative relation to the active vibrator, and out of operative relation to the inactive vibrator.
- 20 13. The combination of ribbon vibrators shiftable alternatively into active position, shifting levers having a lost motion connection with the vibrators to permit the latter to vibrate independently of the shifting levers, and means to simultaneously actuate said levers to reverse the vibrators.
- 25 14. The combination of ribbon vibrators shiftable alternatively into active position, shifting levers having a lost motion connection with the vibrators to permit the latter to vibrate independently of the shifting levers, means to simultaneously actuate said levers to reverse the vibrators, an actuator for said vibrators, and means to maintain said actuator in operative relation to the active vibrator.
- 30 15. The combination of ribbon vibrators, shifting levers having means to engage the vibrators, a bar connecting said levers to simultaneously shift them and thereby move one vibrator to active position as the other is moved to inactive position, a key for shifting said bar, and means to vibrate each vibrator when in said active position, while the other vibrator is held at rest in inactive position.
- 35 16. The combination of ribbon vibrators, a key-actuated rock shaft, shifting devices operatively connected to said shaft for shifting the vibrators alternatively to active position, an actuator for the vibrators, and connections between said actuator and the rock shaft for shifting the actuator alternatively into operative relation with the vibrators.
- 40 17. In a typewriting machine, the combination of a platen, a shift rail on which the platen runs, a universal bar, a vibrator lever connected to shift with the shift rail, operating connections between the universal bar and said lever, ribbon vibrators, means to shift said lever laterally into and out of operative relation with the ribbon vibrators, and means to shift said vibrators alternatively into active position.
- 45 18. The combination of ribbon vibrators, means to shift said vibrators alternatively into active position, an actuator for said vibrators, means to maintain said actuator in operative relation to the active vibrator, and a device to lock the vibrators in an intermediate inactive position, said actuator being disconnected from the vibrators when the latter are in said inactive position.
- 50 19. In ribbon mechanism, the combination of interchangeable ribbon vibrators, means to move them alternatively into active position, and means to vibrate the vibrator which is in active position while the other vibrator remains at rest in inactive position.
- 55 20. The combination of a type-bar segment, a guide plate mounted on the rear of said segment and spaced therefrom, ribbon vibrators between said guide plate and segment, and provided with means co-operating with the guide plate and segment respectively to guide the vibrators in their vertical movement, and means to shift either vibrator downward and move the ribbon carried thereby into the space between said guide plate and segment.
- 60 21. The combination of a type-bar segment, a guide plate thereon, ribbon vibrators between said segment and guide plate, said vibrators movable alternatively to active position, said guide plate being offset from the segment to form a pocket for the ribbon carried by the inactive vibrator, and means forming slot and pin connections between the vibrators and the segment and said plate.
- 65 22. In ribbon mechanism, the combination of ribbon guides, a platen shiftable to upper and lower case positions, a vibrator lever shiftable bodily up and down with the platen, means for vibrating said lever, a slide on which said lever is mounted, and means to operate said slide and shift said lever bodily into operative connection with either ribbon guide and out of operative connection with the other guide, so that either ribbon guide may be vibrated by said lever while the other guide remains inactive.
- 70 23. In a typewriting machine, the combination of a universal bar, a shiftable platen, a ribbon vibrator, an actuator for vibrating said vibrator over the platen, said actuator shiftable with the platen and carrying the vibrator with it to maintain the same relative position of the vibrator and platen.

when the latter is shifted, means to shift said vibrator into and out of operative position, means to automatically disconnect the actuator from said vibrator when the vibrator is shifted to inoperative position, and a connection between the universal bar and said actuator.

24. In ribbon-vibrating mechanism, the combination of vertically vibratable ribbon guides located one in front of the other and having offset portions providing a space between the said guides, an actuating lever to vibrate said guides, means to bodily shift said lever laterally in said space into positions to coöperate with either of said guides, and means to cause said lever, when rotated about its pivot, to automatically effect a driving connection with the ribbon guide toward which it has been shifted.

25. In a typewriting machine, the combination with a ribbon guide, of a key to shift said guide to and from an operative position from which it may be vibrated over the printing point, an actuator to vibrate said guide from said operative position, and means to connect said actuator and guide when the latter is moved to operative position, and to disconnect the actuator and guide when the latter is moved away from said operative position.

26. In a typewriting machine, the combination with ribbon guides through each of which a separate ribbon may be guided, means to shift either ribbon guide to an active position, the other guide being in an inactive position with its ribbon below the range of movement of the active guide, and vibrating means for said ribbon guides operative to vibrate the active guide and move its ribbon over the printing point while the inactive guide remains at rest in said inactive position.

27. In a typewriting machine, the combination with a type-bar segment, of a ribbon guide mounted on said segment for vertical vibrating movement to vibrate a ribbon carried thereby over the printing point, said ribbon guide shiftable downwardly to an inoperative position in which the guide is located below the upper surface of the segment, and shiftable upwardly to an operative position in which the guide projects above the segment, a vibrator lever for vibrating said guide, operatively connected to the guide when the latter is in said operative position, and means for maintaining said lever disconnected from the guide when the latter is in said inoperative position.

28. In a front-strike typewriting machine, the combination with a vertically-disposed type-bar-segment, of ribbon guides mounted on said segment and shiftable to bring either guide to an operative position in which it extends above the segment while the other guide is held in an inoperative position, an

actuator to vibrate the operative guide and means for automatically disconnecting said actuator from one guide and connecting it to the other when the positions of the guides are reversed, so that said actuator is always 70 operatively connected to the operative guide.

29. The combination with a type-bar segment and a guide plate thereon, of ribbon guides supported and guided between said segment and guide plate, said guide plate 75 being offset from the segment to form a slot extending laterally beyond the ribbon guides, means to shift either ribbon guide upwardly to an operative position in which its ribbon is held above the segment, and to concomitantly shift the other guide downwardly to an inoperative position in which its ribbon is carried into said slot, and means to vibrate the operative ribbon guide while the other guide is held at rest in its inoperative position.

30. In a front-strike typewriting machine, the combination with a vertically-disposed type-bar segment, of ribbon guides located behind said segment and shiftable upwardly 90 alternatively to an active position, each ribbon guide, while in active position, projecting above the segment and holding its ribbon above the segment while the other guide holds its ribbon below the upper surface of 95 the segment, and actuating means for the ribbon guides to vibrate the operative guide while the other guide remains at rest in its lowered position.

31. In a typewriting machine, the combination with a type-bar segment, of a guide plate mounted thereon and offset therefrom to form a slot to receive either one of a pair of ribbons, ribbon guides between said segment and guide plate through which said 100 ribbons are threaded, said guide plate having an additional offset in which the ribbon guides are supported and guided, means to shift either ribbon guide to an operative position above said guide plate and segment, and concomitantly shift the other ribbon guide downwardly to carry its ribbon into 110 said slot, and means to vibrate the operative ribbon guide.

32. In a typewriting machine, the combination with a platen shiftable to upper and lower case positions, of ribbon guides alternatively shiftable to an operative position, shifting means for shifting said guides, said 115 shifting means mounted to move up and down with the platen and thereby maintain a constant relation between the operative ribbon guide and platen as the latter is shifted, an actuator for vibrating the operative ribbon guide, said actuator mounted 120 to shift up and down with the platen, and means to disconnect said actuator from the active ribbon guide when the latter is moved from active to inactive position and to connect said actuator with the other ribbon 125 130

guide when the latter is moved from inactive to active position.

33. In a typewriting machine, the combination with ribbon guides, of shifting mechanism for shifting either ribbon guide to an operative position, an actuator for vibrating the operative ribbon guide, said shifting mechanism comprising a key-operated rock shaft and means operated thereby to move one guide to operative position when the rock shaft is rocked in one direction, and to move the other guide to operative position

when the rock shaft is rocked in the opposite direction, and a connection between said rock shaft and said actuator for shifting the actuator into operative relation to each ribbon guide when the latter is moved to operative position, whereby said actuator is always operatively connected to the operative guide. 15
